US00D549688S

(12) **United States Design Patent** (10) Patent No.: **US D549,688 S**
(45) Date of Patent: **** Aug. 28, 2007**

(54) **HEADPHONE**

(75) Inventor: **Satoshi Suzuki**, Tokyo (JP)

(73) Assignee: **Sony Corporation**, Tokyo (JP)

(**) Term: **14 Years**

(21) Appl. No.: **29/251,489**

(22) Filed: **Jan. 10, 2006**

(51) LOC (8) Cl. **14-01**

(52) U.S. Cl. **D14/205**

(58) Field of Classification Search **D14/188, D14/192, 205, 206, 223; 181/129, 130; 379/110.01, 379/430, 431, 428.02; 381/371, 372, 376, 381/378, 379, 377; 455/575.2; 24/3.1; 2/209, 2/423; 74/822**
